UNITED STATES PATENT OFFICE

CLINT M. COPELAND, OF MARLAND, OKLAHOMA

BEAM HANGER

Application filed July 13, 1927. Serial No. 205,386.

This invention relates to a beam hanger for oil wells and the like. The primary object of the invention is to provide a beam hanger which will provide a substantially straight pull on the sucker rods during a pumping operation. The sucker rods are operated from a walking beam. Since the toe of the walking beam swings in an arc, there is a tendency for the hanger to swing in an arc, particularly on the up-stroke and throw the rods against the tubing. My invention contemplates a hanger which will insure a substantially vertical pull of the rods during the up-stroke of the walking beam and which will maintain the vertical movement on the down-stroke.

The novelty of the invention will be better understood by reference to the following description in connection with the accompanying drawings in which:

Fig. 1 is a side elevational view of the hanger applied to the forward or toe end of the walking beam, the two extreme positions of the walking beam being shown in dotted lines and

Fig. 2 is a front view of the hanger and the end of the walking beam.

The walking beam 1 is of usual construction with notches 2 and 3 at the toe end 30 thereof to receive the trunnions 4 and 5 of the hanger. A loop or eye 6 is carried by the trunnions so that the hanger can be lifted to apply it and to remove it. The usual plate 7 may be used for holding the trunnions in place. The trunnions are really the ends of a rock shaft from the center of which is hung a rod 8 having a rearwardly projecting rod 9 extending at an acute angle in an upward direction with an upwardly and forwardly extending portion 10 forming an elbow 11. The upper end of the extension 10 is connected to the rod 8 by a transverse portion 12. The portions 9, 10 and 12 can all consist of a single rod welded to the rod 8, the whole forming a frame in the notch or slot 13 with the elbow 11 resting against the end 14 of the slot 13 as shown in Fig. 1. At the lower end of the rod 8 is a transverse hanger shaft 15 from which are suspended two rods 16 and 17

loosely mounted upon the cross-bar or shaft 15 and connected at their lower ends by the cross-bar 18 which carries the polish rod 19. The elbow 11 serves as a cam for maintaining the lower end 20 of the rod 8 in a fixed vertical plane during the up-stroke of the walking beam 1, so that the frame consisting of the members 15, 16, 17 and 18 will rise in a straight vertical plane to provide a substantially straight vertical pull on the sucker rods. The pull is not in a true straight vertical plane because the camming surface 11 is constantly adjacent to the same point in the base of the groove at the end of the walking beam causing the point 15 to move in a slightly arcuate path, but the swing of the end of link 8 is only about one and one-half inches in a five foot stroke so for all intents and purposes, it can truly be said that the movement of the end of the link 8 is substantially in a vertical plane. On the down-stroke, the weight of the rods will cause them to move in the same vertical plane, therefore, liability of the rods moving out of vertical plane will be eliminated. The offset angular portion of the hanger formed by the members 9, 10 and 11 form an elbow which bears against the end 14 of the slot 13. The angle of the elbow riding on the end 14 maintains the rod 8 in a substantially vertical line during the swing of the walking beam and thereby insures a direct vertical pull on the sucker rods.

What I claim and desire to secure by Letters-Patent is:

1. A beam hanger comprising a rod having means for attachment to a walking beam having a slot in its end, a rearwardly projecting elbow-shaped camming portion on the rod to bear against the base of the slot in the walking beam and means for attaching the rod to a polish rod.

2. A beam hanger comprising a rod having means for attachment to a walking beam having a slot in its end, a rearwardly projecting offset elbow-shaped camming portion on the rod to bear against the base of the slot in the walking beam, means for attaching the rod to a polish rod, said means comprising a hanger frame loosely connected at

its top to the first named rod and means on the lower end of the rod for attachment to a polish rod.

3. A beam hanger comprising an irregular shaped body having an angular offset portion adapted to bear against the base of a slot in the end of a walking beam and an end portion to engage a notch in the walking beam so that the lower end of the body portion will travel in a substantially vertical plane during the upward swing of the forward end of the walking beam.

4. A beam hanger comprising an irregular shaped body having an angular offset portion adapted to bear against the base of a slot in a walking beam and an end portion to engage a notch in the walking beam so that the lower end of the body portion will travel in a substantially vertical plane during the upward swing of the forward end of the walking beam and a polish rod supporting frame loosely fastened to the lower end of the body portion.

5. In combination, a walking beam having a longitudinal slot in its forward end and a beam hanger comprising a straight rod, trunnions suspending the straight rod from the walking beam and an angular offset portion carried by the rod for engagement with the walking beam in the rear end of the slot so that the lower end of the straight rod will travel in a substantially vertical plane during the upward swing of the walking beam.

In testimony whereof I affix my signature.
CLINT M. COPELAND.
